(57) **CLAIM**

The ornamental design for a mould for candle holder, as shown and described.

DESCRIPTION

FIG. 1 is a front perspective view of a mould for candle holder design showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The broken lines throughout the drawing figures depict portions of the mould for candle holder that form no part of the claimed design.

1 Claim, 8 Drawing Sheets
